ington, N. J., a corporation of New Jersey

Application May 12, 1949, Serial No. 92,762

3 Claims. (Cl. 12—142)

1

This invention relates to the manufacture of shoes having predetermined uppers, i. e., shoes in which the upper is pre-cut to fit the last.

In practicing the conventional processes of manufacturing various types of shoes having predetermined uppers, the upper is pre-cut to a size such that when a shoe bottoming member or members—which may, for example, take the form of a sock lining or other type of sole member, platform cover strip or welt—is stitched thereto prior to the placing of the shoe on the last preparatory to completing the shoe, the upper generally snugly fits the last. However, in the conventional processes the upper is not conformed to the last by the placing of the upper and attached bottoming member or members on the last in the sense that the stretch in the upper materials or any inaccuracies in the size of the upper resulting from inaccurate patterns, dies, cutting and fitting are removed from the upper. Consequently, shoes with predetermined uppers made by the conventional processes frequently do not fit the foot nor retain their shapes as well as do conventionally lasted shoes, such as Goodyear welt shoes.

It is a principal object of this invention to provide a method of manufacturing various types of shoes having predetermined uppers by the practice of which the previously mentioned stretch and inaccuracies in the upper may be eliminated from the upper prior to the attachment thereof to the shoe bottoming member or members. The invention contemplates the conforming of the upper to a special last or form which is shaped substantially like a normal last, with the exception that a portion of or the entire bottom of the special last has added thereto a thickness of predetermined amount substantially equal to the allowance on the upper required for attaching the upper to the shoe bottoming member or members. The upper is trimmed along a line corresponding to the feather line, or the corner of the bottom of the added thickness of the special last, thus resulting in a pre-lasted upper from which the stretch and inaccuracies have been removed and which is shaped substantially like the normal last, plus the required allowance for attachment of the shoe bottoming member or members.

The process is applicable to the manufacture of any type of shoe having predetermined uppers, e. g., prewelts, stitchdowns, and platform soles, and it may be practiced with respect to the entire upper or any desired part thereof. A particular advantage of the process is that it is applicable to the manufacture of closed toe shoes.

2

The process will be illustrated as applied to the manufacture of platform and prewelt shoes having closed toes and closed heels.

Reference is now made to the accompanying drawings wherein,

Fig. 1 is a side view of a normal last;

Fig. 2 is a side view of a special last which is substantially equal in size and shape to the last of Fig. 1 plus an added thickness of material over the entire bottom thereof;

Fig. 3 shows the upper of a shoe, the vamp and quarters of which are provided with a lasting allowance;

Fig. 4 shows the upper on the special last after the pulling over operation;

Fig. 5 shows the bottom of the shoe on the special last after the side lasting and the bed lasting operations, and the trimming of the upper while on the last;

Fig. 6 shows the marking of the quarter lining along the bottom of the added thickness on the special last while the upper is on the special last;

Fig. 7 shows the alternative method of trimming the upper, viz., after it has been removed from the special last;

Fig. 8 shows a special last with the added thickness on the bottom forepart only;

Figs. 9 and 10 are partial sectional views taken on the lines IX—IX and X—X, respectively, of Fig. 11 which is a side view of a completed slip lasted platform shoe;

Fig. 12 is a partial transverse sectional view through the toe of a slip lasted prewelt shoe; and

Fig. 13 is a partial transverse sectional view through the toe of a prewelt shoe.

Considering first the application of the process to the manufacture of closed toe platform shoes, in Fig. 1 there is disclosed a last 10 which is identical in all respects with the normal last used in conventional methods, which last, as is well known, is inserted in the shoe after the attachment of the upper to the sock lining (and cover strips when a platform shoe is being made) prior to the completion of the bottom of the shoe. This last is referred to hereinafter as the "normal last."

In Fig. 2 there is disclosed a last 12 which is substantially identical in size and shape with the normal last 10, except that there is added to the bottom of the last 12 material 14 substantially equal in thickness to the width of the seam allowance on the upper necessary for attaching the upper to the sock lining. The addition of the thickness 14 produces a last the bottom of which has a corner or feather 16 which, in the illustrated case, extends completely around the last.

If desired, a last or form may be made integrally incorporating the added thickness. Regardless of how made, the oversize last or form 12 is referred to hereinafter as the "special last." That portion of the special last corresponding to the normal last need not necessarily be identical in size and shape with the normal last since it may be desirable to have the special last of somewhat less peripheral extent around the toe than in the case of the normal last, because of the tendency of the lower margin of the upper of the shoe to flatten out or stretch when the sock lining or other shoe bottom member is stitched thereto. To compensate for the lesser volume of such a last, the vertical height thereof may be slightly increased, or the thickness of the material added to the bottom thereof may be increased.

In Fig. 3 there is disclosed an upper including a vamp 18, lining 20, quarters 22, counter lining 24 and counter 25 in the counter pocket formed by the quarters and quarter lining.

The patterns from which the vamp, vamp lining, quarters and quarter lining are cut are drafted as in conventional shoemaking, except that provision is made for a lasting allowance 26 of approximately one-half inch on the vamp and its lining and a lasting allowance 27 of approximately a quarter inch on the quarters and quarter linings. A toe box 28, preferably of the activated or mulled type, is provided.

The upper is then assembled on the special last 12 in the usual manner, and the toe box 28 is inserted between the vamp 18 and its lining 20, unless this insertion has been previously made. The upper is then conformed to the last. The manner in which this may be accomplished may be practiced in a wide variety of ways. One satisfactory method of conforming the upper to the special last 12 is the presentation of the last and upper to a conventional pulling over machine. The pulling over operation stretches the entire upper forward of the last and generally conforms the upper to the last, particularly rearward of the tip line of the shoe, and the machine automatically drives upstanding tacks through the lasting allowance 26 into the bottom forepart of the special last to hold the upper in its pulled over position. In Fig. 4 the tacks are numbered 29 and shown to be seven in number in the illustrated case. The usual tack driven in the heel seat in the prior assembling operation is designated 30 in Fig. 4, and the added thickness of material 14 on the bottom of the last is seen, in the illustrated case, to be held on the last by tacks 15.

The shoe may then be side lasted with upstanding tacks 31, as shown in Fig. 5. This lasting, if used, may be accomplished by hand or machine. If desired, prior to such lasting, in the making of lined shoes, adhesive may be applied between the lining and upper to secure the same together in the regions rearwardly of the toe box, thus facilitating later attachment of the upper to the sock lining.

The shoe may then be lasted forward of the tip line by the use of a conventional bed lasting machine and inserting the upstanding tacks 32, also seen in Fig. 5, which shows the upper at the end of such operation. Prior to this operation all except the two rearmost tacks 29 inserted by the pulling over machine may be removed. It will be seen that the forepart of the upper has been conformed to the last 12 and the rear part has been snugly fitted to the last. If desired, the

shank and heel of the upper may also be lasted in, although not so shown in the drawings.

It will be appreciated that the foregoing described lasting of the upper to the last or form produces an upper from which the stretch has been removed and which is shaped above the corner 16 of the special last 12 substantially like the normal last 10, except that a seam allowance equal to the thickness of the added material 14 is added to the upper. It will be appreciated that this conforming of the upper to the last may be accomplished by various other methods than those set forth hereinbefore without departing from the substance of the invention.

The upper is then trimmed along a line corresponding to the corner 16 of the last. This trimming may be accomplished with the upper on or off the last, and may be accomplished by hand or machine. Fig. 5 shows the trimming of the upper while on the last, in which case the cutting implement 33 is employed to trim the vamp 18, lining 20, toe box 28, quarters 22, quarter lining 24 and counter 25 along a line corresponding to the corner 16 or bottom of the last 12.

When the trimming is done off the last, in any part of the shoe where the lasting allowance of the upper has not been lasted in over the bottom of the last, e. g., at the rear of the shoe shown in Fig. 6, a line 16a may be drawn along the corner 16 of the last on the inside of the quarter lining by a suitable marking implement 34. The upper may then be removed from the last and trimmed along the line 16a and crease 16b shown in Fig. 7, the latter being formed on the lining by the corner 16 of the bottom of the last 12 in the region where the lasting allowance of the upper has been lasted in over the bottom of the last. It will be appreciated that in the event the upper has been so lasted in all around the shoe, the crease 16b would be formed all around the inside of the same. If desired, the trimming may be made along the crease 16c formed on the outside of the upper.

The preceding described process produces an upper for a shoe from which the stretch and inaccuracies have been removed and which is shaped substantially like the normal last 10, except that the required seam allowance is added thereto.

The invention also contemplates applying the method to only the forepart or only the toe end of an upper. Considering the practice of the invention as applied to the forepart only of the shoe, an upper is provided having a lasting allowance of approximately one-half inch forward of the ball line and cut to size rearward of the ball line in the conventional manner, i. e., to fit the normal last 10 of Fig. 1 with the usual seam allowance. Correspondingly, the special last 12 (Fig. 8) has added to the bottom of the forepart a thickness of material 50 equal to the desired seam allowance. The upper is assembled on the special last 12, the toe box inserted, and the upper is pulled over and the forepart lasted in. The forepart of the upper is then trimmed either on the last or off the last, all as previously set forth. It will be appreciated that after the trimming operation, the upper will have been conformed to the last and have the required seam allowance around its entire bottom.

In the event that the process of the invention is employed only at the toe of the shoe, it is merely necessary that the vamp rearward of the tip line and the quarters be cut in the manner usually employed, for example, in prewelt shoemaking, and the vamp forward of the tip line

be cut with the lasting allowance of approximately one-half inch. A special last substantially identical in size and shape with the normal last 10 is employed, except that it has added thereto the additional described thickness forward of the tip line. The upper is assembled on the last, pulled over, lasted in and trimmed, all as previously set forth.

Of course the invention may be practiced in the forepart or at the toe end only of the shoe and the remainder of the shoe may be lasted in any desired manner.

Having prepared the upper as previously explained, the shoe may be completed according to conventional methods. If not previously inserted, the counter 25 may now be put in the counter pocket, and as shown in Figs. 9, 10 and 11, the bottom member or sock lining 60 is attached to the vamp, quarters, linings, toe box and counter by the seam 62 which extends completely around the shoe, and the front and rear cover strips 64 and 66 are united to the upper and sock lining by the seam 68 which also extends completely around the shoe. If desired, the trimming of the upper and the attachment of the sock lining and cover strips can be done simultaneously. The normal last 10 is then inserted in the shoe, the platform 70 is laid, covers 64 and 66 lasted in, and outsole 72 and heel 74 attached to the shoe. The bottom of the shoe may, of course, be completed in any other desired manner.

Prewelt shoes may be made according to the method of this invention in the same manner as the platform shoe described except that as shown in Fig. 12, a welt 80 is substituted for the platform cover strips, and the outsole 84 is attached by the outseam 86 passing through the outsole and welt.

In the event the process of this invention is employed to make prewelt shoes, as shown in Fig. 13, the special last may be produced by adding to the bottom of the normal last a thickness of material equal to the combined thickness of the insole 94 and inturned margin 18a of the upper. The upper is provided with a lasting allowance as previously explained, the upper is lasted over the special last, trimmed, and is then ready for attachment of the welt 90 by seam 92 which passes through the inturned margins of the upper members and welt. The shoe may then be completed in the conventional manner, e. g., the insole 94 may be placed on the bottom of the normal last 10, the upper assembled on the last, filler 96 applied and outsole 98 attached by the outseam 100.

It will be readily appreciated that uppers for stitchdown and other types of shoes may be made in much the same manner as just explained. It will be noted that the thickness of material added to the bottom of the normal last in preparing the special last will vary according to the construction of the shoe being made.

Although the method of this invention has been illustrated in connection with the making of closed toe, closed heel shoes with box toes and counters, it will be appreciated that it is equally applicable to the making of shoes of other types. However, when applied to closed toe or closed heel shoes, it is particularly advantageous in that the heel or toe of the shoe, as the case may be, is well formed. By the process it is possible to make closed toe shoes on the more extreme styles of lasts, such as high heel and wall lasts.

In the manufacture of certain types of shoes

it may be desirable to dispense with the insertion of the normal last in the shoe. Also, in some cases it may be desirable to employ a special last which corresponds to only a part of a normal last, e. g., the forepart or toe.

It will be appreciated that this invention discloses a method for making shoes having predetermined uppers, the whole or any part of which may be subjected to the method to eliminate stretch and inaccuracies from the upper prior to attachment of the upper to a shoe bottoming member. Where the process is practiced with respect to a part of a shoe only, the remainder of the shoe, e. g., the shank and heel, may be completed in any desired manner. The method is applicable to the manufacture of any type of shoe incorporating a predetermined upper, and is not limited to the types of shoes disclosed herein.

Having thus described my invention, what I claim as new and desire to secure by Letters Patent of the United States is:

1. That improvement in methods of making shoes which comprises the steps of providing a form which is substantially equal in size and shape to the desired size and shape of the entire interior of the completed shoe plus an added increment of predetermined thickness on the bottom thereof, conforming an upper to that part of the form having the added thickness, and trimming the upper along a line corresponding to the bottom of the added thickness.

2. That improvement in methods of making shoes which comprises the steps of providing a form which is substantially equal in size and shape to the desired size and shape of the entire interior of the shoe being made plus an added increment of predetermined thickness on the bottom thereof, conforming an upper to that part of the form having the added thickness including turning the lasting margin of the upper over the bottom of the additional thickness, removing the upper from the form, and while the upper has no last or form therein trimming it along the crease formed by the said over turning.

45 3. That improvement in methods of making shoes which comprises the steps of providing a form which is substantially equal in size and shape to the desired size and shape of the interior of the completed shoe plus an increment of predetermined thickness on the bottom thereof, shaping an upper over the form, turning the bottom margin of the forepart of the upper over the edge of the bottom of the form in order to form a crease therein, scribing a mark on the 50 rear part of the upper along the edge of the bottom of the form, removing the upper from the form, trimming the forepart of the upper along the crease formed therein, and trimming the rear part of the upper along said mark.

60 JAMES D. CHANDLER.
